UNITED STATES PATENT OFFICE.

HENRY SPENCER BLACKMORE, OF MOUNT VERNON, NEW YORK.

FORMIC-ALDEHYDE PREPARATION AND PROCESS OF MAKING SAME.

No. 889,171.

Specification of Letters Patent.

Patented May 26, 1908.

Original application filed April 18, 1903, Serial No. 153,330. Divided and this application filed May 20, 1907.
Serial No. 374,578. (Specimens.)

To all whom it may concern:

Be it known that I, HENRY SPENCER BLACKMORE, a citizen of the United States, residing at Mount Vernon, in the county of 5 Westchester and State of New York, have invented certain new and useful Improvements in Formic-Aldehyde Preparations and Processes of Making Same, of which the following is a specification, being a division of 10 Serial No. 153,330, filed April 18, 1903.

This invention relates to a new article of manufacture or composition of matter for disinfecting, germicide, antiseptic, and medicinal purposes, and consists of a mixture, 15 compound, or solution, of formic aldehyde or its polymerids in a methyl ester, such as methyl-benzoic ester, methyl-salicylic ester, etc., or compositions containing methylesters, which compounds or compositions may or 20 may not be associated with other vehicles or medicating agents, the object being to produce a solution of formic aldehyde or its polymerids, which will be of permanent 25 nature in relation to spontaneous decomposition and which, in fluid condition, may be readily utilized without producing disagreeable effects.

As a specific illustration of my new composition of matter and the manner in which 30 the same is made, I will take for example the production of a solution of formic aldehyde in methyl-salicylic ester (methyl-salicylate). The manner in which I prefer to produce this solution of formic aldehyde 35 or its polymerids is to place the desired methyl ester, such as methyl-salicylic ester, in a proper container and expose it to the presence of formic aldehyde under increased pressure at the same time agitating it, 40 whereby the formic aldehyde becomes absorbed, occluded, or retained therein. When the ester has become saturated with formic aldehyde it is removed, the formic aldehyde content ascertained by test, and the composition 45 diluted with more ester, or other diluent, to obtain the percentage content of the formic aldehyde desired. The polymerids of formic aldehyde, such as para-formaldehyde or trioxymethylene, may be 50 dissolved in the ester, preferably by the action of heat, producing compounds not departing from the spirit of my invention, as, upon heating in the formation of the composition, formic aldehyde is generated in the 55 presence of the methyl ester and absorbed

thereby; and the composition is found to have a like disinfectant, germicide, antiseptic, and medicinal property, and to all intents and purposes may be considered, and is herein included, as an equivalent composition in accordance with my invention. 60

I have found it of advantage to employ compositions containing methyl esters and formic aldehyde diluted with a vehicle, such as camphor oil, in which case it is found to 65 act with satisfaction as an aerial disinfectant, inasmuch as the camphor oil and methyl ester is volatile at ordinary atmospheric pressure and temperature and saturates the air coming in contact therewith with formic 70 aldehyde and the methyl ester, which, having a pleasant characteristic odor, perfumes the air and obviates the disagreeable pungent effect, which usually accompanies the application of formic aldehyde *per se*. 75

I have found that formic aldehyde and its polymerids may be readily assimilated with the methyl oxy-acid esters, which, having characteristic odors, serve to disguise the formic aldehyde when applied, without deteriorating or destroying its effectiveness 80 as a disinfectant. I have also found that the methyl oxy-acid esters not only act as a solvent of the formic aldehyde, or its polymerids, but may be employed as a carrier or 85 solvent agent to introduce formic aldehyde into other vehicles in which it is less soluble, and in which event solutions of formic aldehyde in methyl esters *per se*, which may be of expensive manufacture, may be employed 90 with economical advantage by adding thereto a less expensive diluent without deteriorating the effectiveness of the disinfectant formic aldehyde or the odorizing or solvent methyl ester. 95

Specifically my invention relates to a solution of formic aldehyde or its polymerids in a methyl ester, such as methyl oxy-acid ester of aromatic character, either *per se* or with other diluents, but is not confined to methyl esters of salicylic acid, as herein specifically described, as I may employ any practical methyl ester or methyl oxy-acid esters, or methyl substitution product of an acid or oxy-acid. It may be noted also that the 100 methyl esters, as a rule, are practically incompatible with water or non-miscible with or repellent thereto. 105

The term "formic aldehyde" employed throughout this specification and claims is 110

intended to include its polymerids, or equivalents, such as para-formaldehyde or triox-methylene, and intermediate polymerization products as well as formic aldehyde *per se*, and the term "methyl ester" to what may be termed a methyl salt or methyl substitution product of an acid or oxy-acid, *i. e.*, a hydrogen acid or an acid containing oxygen, which methyl esters may be either obtained from nature or artificially or synthetically prepared.

I am aware that oil of wintergreen has been added to compounds formed by the action of formic aldehyde on gluten and gelatin for the purpose of perfuming it, also that oil of wintergreen has been added to dental preparations containing caustic alkali and formicaldehyde, whereby it is transformed into alkali salicylate and methyl alcohol, but in neither of these cases does the resultant product comprise formic aldehyde and a methyl ester, as herein described, but consists only of decomposition products of either, or both, of the essential ingredients of my composition, *viz.*, formic aldehyde and methyl ester.

It may be noted that formic aldehyde, which is a gas, unites or combines more readily with the methyl esters and becomes more readily assimilated, or retained, or occluded therein in a more permanent manner and in a larger percentage without danger of polymerization than is the case with aqueous solutions.

The largest percentage of formicaldehyde obtained under ordinary conditions in aqueous solution does not exceed 40%, whereas methyl esters have the property of transforming or occluding gaseous formic aldehyde into a liquid condition with such avidity and permanency that solutions even up to 80% formic aldehyde have been produced without polymerization into solid products, at the same time the valuable disinfectant and germicide properties of the formic aldehyde have not been deteriorated, but in fact seem to be enhanced by its union or composition with the methyl ester solvent or vehicle.

The term "containing methyl ester" as employed in this specification and claims, with reference to the vehicle for the formic aldehyde has reference to methyl esters *per se*, or inert diluent containing the same in any desired proportion, and the term "inert" as employed herein is intended to imply a diluent inert with reference to the formic aldehyde and methyl ester content of the composition.

While my invention is particularly applicable to the employment of methyl esters of oxy-acids of the aromatic series, such as benzoic, salicylic, cinnamic, etc., which methyl esters are volatile, aromatic, and wa-

this specific class of methyl oxy-acid esters, but reserve the right to employ any methyl ester, be it either fluid or solid, as a solvent or vehicle, either *per se* or in composition with other diluents, for formic aldehyde or its polymerids.

Where reference herein is made to dissolving formic aldehyde in methyl esters it is intended to imply and does imply that formic aldehyde gas is transformed, converted, condensed, or reduced, from a gaseous to a liquid or liquefied condition, by the action of, or by its assimilation or its association with, methyl esters.

Having now described my invention, what I claim as new and desire to secure by Letters Patent is:—

1. A new composition of matter comprising a methyl ester and formic aldehyde.

2. A new composition of matter comprising a methyl ester, formic aldehyde, and a diluent.

3. A new composition of matter comprising a methyl ester, formic aldehyde, and camphor oil.

4. A new composition of matter comprising a methyl oxy-acid ester and formic aldehyde.

5. A new composition of matter comprising a methyl oxy-acid ester, formic aldehyde, and a diluent.

6. A new composition of matter comprising a methyl oxy-acid ester, formic aldehyde, and camphor oil.

7. A new composition of matter comprising an anhydrous methyl ester and formic aldehyde.

8. A new composition of matter comprising an anhydrous methyl ester, formic aldehyde, and a diluent.

9. A new composition of matter comprising an anhydrous methyl ester, formic aldehyde and camphor oil.

10. A new composition of matter comprising an anhydrous methyl oxy-acid ester, and formic aldehyde.

11. A new composition of matter comprising an anhydrous methyl oxy-acid ester, formic aldehyde and a diluent.

12. A new composition of matter comprising an anhydrous methyl oxy-acid ester, formic aldehyde, and camphor oil.

13. A new composition of matter comprising a volatile methyl ester and formic aldehyde.

14. A new composition of matter comprising a volatile methyl ester, formic aldehyde and a diluent.

15. A new composition of matter comprising a volatile methyl ester, formic aldehyde, and camphor oil.

16. A new composition of matter comprising a volatile oxy-acid ester and formic aldehyde.

17. A new composition of matter comprising

- ing a volatile methyl oxy-acid ester, formic aldehyde, and a diluent.
18. A new composition of matter comprising a volatile methyl oxy-acid ester, formic aldehyde, and camphor oil.
19. A new fluid composition of matter comprising formic aldehyde and a methyl ester.
20. A new fluid composition of matter, comprising formic aldehyde, a methyl ester, and a diluent.
21. A new fluid composition of matter comprising formic aldehyde, a methyl ester, and camphor oil.
15. 22. A new fluid composition of matter, comprising formic aldehyde, and methyl salicylic ester.
23. A new fluid composition of matter, comprising formic aldehyde, methyl salicylic ester, and a diluent.
24. A new fluid composition of matter, comprising formic aldehyde, methyl salicylate, and camphor oil.
25. The process of making the new composition of matter herein set forth, which 25 consists in dissolving formic aldehyde in a methyl ester under super-atmospheric pressure.
26. The process of making the new composition of matter herein set forth, which 30 consists in dissolving formic aldehyde in methyl salicylic ester under super-atmospheric pressure.

In testimony whereof I affix my signature in presence of two witnesses.

HENRY SPENCER BLACKMORE.
